MARCUS MAZER, OF PHILADELPHIA, PENNSYLVANIA.

ACOUSTIC PANEL.

Application filed January 19, 1928. Serial No. 247,955. This invention relates to acoustic panels, adapted to be mounted in the ceiling and walls of buildings for correcting defects in the acoustics of the structure.

An object of the present invention is to provide a panel which may be made of the desirable size for mounting on a ceiling or wall and which is constructed such that it may be given the desired finish of the ceiling or wall and wherein the acoustic material for absorbing sound is covered by an outer layer which forms the surface of the panel.

Architects seriously object to breaking up of a ceiling or wall into a multiplicity of small panels as it destroys the particular scheme of decoration. Therefore, it is essential to have large panels, frequently of the same general dimension as the ceiling or wall, and it is impossible to build such large panels and subsequently mount them or to carry the panels through door or other small openings into the chamber in which they are to be installed.

This invention provides a panel made up of a plurality of units or sections which comprise a single unitary panel.

Another object of the invention is to provide a panel of such construction that it is capable of being knocked-down or folded so as to pass through door-ways and the like into position for mounting, and wherein the knocked-down or foldable structure of the panel is so arranged that it may be utilized in stretching and maintaining taut the surface covering of the panel when the latter is in place; thereby retaining the esthetic appearance of the ceiling or wall surfaces with which the architects are greatly concerned.

Another object of the invention is to provide a panel which may comprise any desired number of frames suitably connected together for folding and which carries the outer surface or covering material for the panel in such manner that when the frames are spread apart or opened the surface material will be stretched and held taut, and to provide panel frames which may be made in any desired dimensions and shapes and in which may be mounted the felt or other suitable acoustic material which may be used.

With the foregoing and other objects in view, the invention will be more fully described hereinafter, and will be more particularly pointed out in the claims appended hereto.

In the drawings, wherein like symbols refer to like or corresponding parts throughout the several views;

Figure 1 is an outer face elevation of a panel constructed according to the present invention, a portion of the outer surface material being removed to show the frame structure.

Figure 2 is an edge view of the panel of Figure 1, a portion of the panel being broken away to show the hinged connection, the dotted lines showing the position of the panel parts as they are stretched or spread for use.

Figure 3 is an enlarged section taken through a portion of one of the frames of the panel, showing the acoustic material mounted therein, and

Figure 4 is a longitudinal section taken through one of the frames of the panel at right angles to the showing in Figure 3.

Referring to the drawing there is shown one form of panel, but it is to be understood that the panel may be made in any desired size and of any desired number of sections hinged together lengthwise or transversely and which are constructed according to the particular size and configurations of the ceiling and walls to which the panels are to be applied.

In the present instance the panel is shown as comprising a pair of frames 10 and 11 substantially similar in construction. The frame 10 is of substantially rectangular form and provided at suitable intervals throughout its length with cross braces 12 which rest upon longitudinal cleats or strips 13 secured at the inner longitudinal sides of the frame 10. Fitted between the longitudinal strips 13 is a sheet or body of sound absorbing material 14 which may be felt or any other suitable material secured by staples 16 at its longitudinal edge portions to the strips 13. It will be noted that the acoustic material 14 lies across the inner faces of the braces 12 and, as shown in Figure 4, is secured thereto by

staples 17 or the like. Staples 18 secure the opposite ends of the acoustic material 14 to the ends of the frame 10.

For the purpose of covering the outer face 5 of the panel and permitting the painting or otherwise treating of the panel to conform to the mural finish of the room or chamber, a surface layer of canvas 19 or other suitable material is stretched over the frames 10 and 11. The frames 10 and 11 are placed together in edgewise contact and are secured together by hinges 20 or the like, which are located 10 toward the outer face or side of the panel so that the panel may break inwardly or away 15 from the normal outer surface thereof. The canvas 19, as shown in Figure 2 particularly, is stretched lengthwise over the frames 10 and 11 and secured taut across the frames when the latter are partly broken or buckled, 20 so that when the frames are forced into alinement, as shown in full lines in Figure 2, the canvas or surface layer 19 is drawn taut and held in such stretched position. The canvas sheet 19 is drawn taut cross- 25 wise of the frames 10 and 11 when the frames are buckled, as shown in dotted lines in Figure 2, because when the frames are stretched or swung into alinement, the longitudinal stretching action on the canvas 19 also con- 30 tracts the canvas sheet as to its width and consequently draws the canvas sheet taut in both longitudinal and transverse directions. The panel may be made up of any suitable 35 number of frames 10 and 11 and the frames may be hinged together in groups and at different sides but in each instance the canvas layer 19 is secured across two or more of the frames in such position that the canvas is stretched when the frames are swung into 40 alinement.

The outer surface of the canvas 19 may be painted or otherwise suitably treated to impart the desired surface coloring or coating to the panel, so as to blend with the wall or 45 ceiling finish.

From Figures 2, 3 and 4 it will be noted that the stretched surface sheet 19 is spaced from the felt sheet 14, and a dead air space 20 is provided between the two, so as to further dampen the vibrations transmitted through the canvas sheet 19 and into the absorbing material 14.

Another advantage in building the panel in sections hinged together, is that a single 55 panel of considerable area may be constructed outside of the building or chamber and may be folded or knocked down after construction and carried through a relatively small door opening or passage into the chamber, and then spread open and stretched into position.

It is obvious that by the above described structure relatively large areas of canvas, in long and wide panels, may be effectively

stretched and held taut from sagging when 65 the panel sections are swung into alinement, a feature which by heretofore practiced means has not been accomplished.

It is obvious that various changes and modifications may be made in the details of 70 construction and design of the above specifically-described embodiment of this invention without departing from the spirit thereof, such changes and modifications being restricted only by the scope of the following 75 claims.

What is claimed is:—

1. An acoustic panel comprising a plurality of sections, means hingedly connecting the sections together to admit the folding of the sections one upon the other, a body of sound absorbing material mounted in each section, and a surface fabric secured over the sections of the panel, said fabric being drawn taut while said sections are in relatively folded or buckled position, said sections adapted to be swung into alinement with one another for drawing said surface fabric taut and stretching the same. 85

2. An acoustic panel comprising a plurality of sections, means for hingedly connecting the sections together for swinging the sections one upon the other into a substantially folded position, cross braces in the sections, longitudinal strips mounted in the sections for supporting the ends of the cross braces, a body of sound absorbing material mounted in each frame between the longitudinal strips and across said braces, and a surface fabric for the panel secured across the sections and secured taut over the sections in a direction at right angles to the axis of the hinged connection between the sections for stretching and maintaining taut the surface material when said sections are swung into alinement. 105

3. An acoustic panel comprising frames, hinges connecting the frames together to admit the buckling and folding of the frames, cross braces in the frames, longitudinal strips in the inner sides of the frames for supporting the cross strips, sound absorbing material mounted in each frame across the braces and between the strips, and a surface fabric secured over the frames and drawn taut at right angles to the hinges when the frames are buckled, whereby when said frames are swung into alinement said surface fabric is stretched and maintained taut. 110

4. An acoustic panel comprising a plurality of hingedly connected sections adapted to be swung into folded and buckled relation, a surface fabric secured over the outer sides of the sections and drawn taut when the sections are in buckled relation, said sections adapted to be swung into alinement for drawing the surface material taut, and sound absorbing material secured in the sections in 115 120 125

spaced relation to the surface fabric to provide an air space between the fabric and the material when the sections are flat.

5. In an acoustic panel, a border frame adapted to enclose a body of sound absorbing material, said frame comprising a plurality of hingedly connected sections adapted to be swung into folded and buckled relation, a surface fabric for covering the body of sound

absorbing material secured over the outer 10 sides of the sections and drawn taut when the sections are in buckled relation, said sections adapted to be swung into alignment as the frame is installed in position for drawing the surface fabric taut over the sound absorbing 15 material.

In testimony whereof I affix my signature.
MARCUS MAZER.
